CLAMP FOR SPLICING MACHINES

Alfred B. Clayton, Indianapolis, Ind., and Alfred N. Iknayan, Grosse Pointe Farms, Mich., assignors to United States Rubber Company, New York, N. Y., a corporation of New Jersey

Application April 8, 1953, Serial No. 347,502

5 Claims. (Cl. 154—9)

This invention relates to clamps for use on trimming and splicing machines for clamping in flattened condition the end portions of tubular stock so that the ends may be trimmed and butt spliced together to form an article such as for example, an inner tube.

The most common type of clamps heretofore used for this purpose consisted of two flat jaws between which the tube stock was clamped. There are, however, certain objections to using this type of clamp particularly for heavy service type inner tubes. When the ends of the tubular stock are clamped between the flat jaws of this type of clamp, the folded lateral edges of the stock are severely crushed and permanently creased with the result that the tube stock is permanently deformed in this region. This deformation often results in cracks on the exterior surface of the tube along the folded edge and also cracks in the interior surface of the tube along the fold when the tube is inflated and cured. This latter cracking is commonly known as "fold breakdown." This cracking of the tubes necessarily results in comparatively weak tubes and if the cracking is severe, the tubes must be discarded.

Attempts have been made to eliminate this crushing and creasing of the rounded, folded edges of the tube stock by making the lower jaw of channel shape and providing undercut recesses in the sidewalls thereof into which the lateral edges of the stock can be inserted. The upper jaw contacts only that portion of the tube extending between the sidewalls and does not contact the folded lateral edges which are inserted in the recesses. Clamps of this structure are shown in U. S. Patent No. 2,145,607 to Nichols. The objection to this type of clamp is that substantially no pressure is applied to the lateral folded edges of the tube stock and when the clamped ends are trimmed and moved into abutting engagement to form a splice, the lateral edges being unrestrained by the clamping jaws tend to be pushed back into the recesses and the resulting splice is very weak adjacent the lateral edges. When it is attempted to form a rindless splice according to the method described in U. S. Patent No. 2,550,566 to Iknayan and Clayton, in which the stock is bulged or extruded out from the faces of the clamps by increasing the pressure between the clamping jaws, the portion of the tube adjacent to the lateral edges being substantially unaffected by increasing the pressure between the clamps do not bulge outwardly to any substantial degree and the resulting splice formed by abutting the bulged out portions together is therefore very weak at the lateral edges of the tube. In addition, the engagement of the upper jaw with the tube section between the lateral edges of the tube rather than across the full width of the tube result in shear marks being formed on the surface of the tube along the edges of the top jaw. In some instances, the top jaw may actually cut into the tube. This latter objection also applies to the use of a laminated clamp of the type shown in U. S. Patent No. 2,040,466 to Christy in which one jaw is

2

made up of a plurality of self-adjusting laminae, as each laminae of the jaw forms a shear mark on the tube.

The primary object, therefore, of the present invention is to provide a clamp having opposed clamping jaws of a novel contour which will engage and apply positive pressure across the full width of the tube stock without crushing or creasing the folded lateral edges of the flattened tube stock so that the ends of the stock may be extruded or bulged outwardly uniformly across the full width of the stock when additional pressure is applied to the clamping jaws and so that the bulged ends of the stock adjacent the lateral edges will not slip back in between the jaws when the ends are forced together in abutting engagement to form a splice.

Other objects and advantages of the present invention will become apparent from the following description when read in conjunction with the accompanying drawings wherein:

Fig. 1 is a perspective view of a set of clamping jaws forming one embodiment of the clamp of the present invention;

Fig. 2 is a partial elevational view of a tube trimming and splicing machine incorporating the clamp structure of Fig. 1;

Fig. 3 is a side elevation taken along the line III—III of Fig. 2 showing the clamping jaws retracted and a piece of tube stock in place on the lower jaw;

Fig. 4 is a side elevation similar to that shown in Fig. 3 but showing the jaws clamping the end of the tube stock;

Fig. 5 is an enlarged partial sectional view showing the details of the contour of the two clamping jaws in clamping position;

Fig. 6 is a plan view of the two clamps of the machine of Fig. 2 showing how the ends of the tubes are extruded or bulged out uniformly across the full width thereof when the pressure on the clamps is increased after the ends have been trimmed;

Fig. 7 is a sectional view taken on the line VII—VII of Fig. 6 showing the extruded or bulged out ends of the tube stock preparatory to their being forced together to form a splice;

Fig. 8 is a sectional view of a slightly modified form of the clamp of the invention; and

Fig. 9 is a sectional view of still another modification of the clamp of the invention.

Referring to the drawings and in particular to Fig. 1 of the drawings, the clamp of the present invention includes an upper jaw 10 and a lower jaw 11 between which the end of a section of flattened inner tube stock may be clamped. As will hereinafter be described in detail, the clamping surfaces of the jaws 10 and 11 are specially contoured so that the tube stock is firmly gripped across the full width thereof without crushing or creasing the lateral folded edges thereof.

As shown in Fig. 2, the jaws 10 and 11 are intended to be used on inner tube trimming and splicing machines for separately clamping the end portions of a section of uncured inner tube stock T so that the ends may be trimmed and butt spliced together to form an inner tube. The particular machine shown in Fig. 2, is of the type disclosed in U. S. Patent No. 2,576,940, but it is to be understood that the jaws 10 and 11 may be used on other types of trimming and splicing machines if desired. One set of jaws 10 and 11 is mounted on each of two movable carriages 13 and 14 of the inner tube trimming and splicing machine in the manner described in detail in U. S. Patent No. 2,576,940. The upper jaws 10 are moved towards the lower jaws 11 to separately clamp the end portions of the inner tube stock T therebetween in opposed relationship by admission of fluid under pressure to cylinders 15 and 16. The ends of the stock T

protruding from the opposed faces of the jaws are trimmed by knives 17 and 18 and the trimmed ends are butt spliced together by admission of fluid under pressure to a cylinder 19 which moves the carriages 13 and 14 toward each other.

Referring again to Fig. 1, the lower jaw 11 has a channel shape recess 20 formed therein. The width of the recess 20 is substantially equal to the width of the particular tube stock T to be clamped. The upper jaw 10 is of substantially the same width as the recess 20 so that it may be slidably received therein between the vertical sidewalls 21 and 22 thereof to clamp the end of the section of inner tube stock T between the under clamping face 23 of the upper jaw 10 and the base surface 24 of the recess 20 of the lower jaw 11.

The upper jaw 10 is secured by welding to a backing plate 25. The backing plate 25 extends beyond each side of the jaw 10 and is bifurcated at each end to provide rectangular slots 26 which receive rectangular guide posts 27. The guide posts 27 are secured to and extend vertically upwardly from the lower jaw 11 adjacent each side of the recess 20. The slots 26 and the guide posts 27 cooperate to insure proper alignment of the upper jaw 10 and the lower jaw 11 when the jaws are moved together to clamp the inner tube stock T.

The backing plate 24 is provided with an opening 28 for receiving a pivot pin 29 so that it may be pivotally attached to the movable platen 30 of the trimming and splicing machine in the manner described in U. S. Patent No. 2,576,940. The upper edges of the channel shape recess 20 of the lower jaw 11 are chamfered as indicated at 31 to facilitate the reception of the upper jaw 10 between the sidewalls 21 and 22.

The base surface 24 of the recess 20 is joined to the perpendicularly extending sidewalls 21 and 22 by smooth, tangential, concave, fillet surfaces 32. The radius of curvature of the surfaces 32 is substantially equal to the radius of the folded lateral edges L of the tube stock T so that the edges of the stock will not be deformed when clamped between the jaws 10 and 11. The under clamping face 23 of the upper jaw 10 is formed by two concave grooves 33 which extend along the opposite lateral edges thereof and a flat surface 34 which joins the two grooves 33. The juncture of the grooves 33 and the surface 34 is carefully rounded to eliminate sharp edges. The radii of the grooves 33 are approximately equal to that of the folded lateral edges L of the tube stock T to be clamped. The depth of the grooves are made substantially less than the thickness of the folded lateral edges L of the tube stock T, but are of sufficient depth to prevent crushing or creasing of the folded lateral edges L of the stock T when the stock is clamped, so that the stock T will be firmly gripped but the lateral folded edges L will not be severely crushed or creased. Good results have been obtained if the depth of the grooves 33 is held to between 15 and 20 percent of the average wall thickness of the uncompressed tube stock T at or near the lateral edge L.

The intersections of the grooves 33 with the sides 35 of the upper jaw 10 form comparatively sharp edges 36, thereby insuring that there are no surfaces when the jaws 10 and 11 are moved together between which the lateral edges L of the tube stock T might be pinched or crushed and insuring that the lateral edges L of the tube stock T will be contained wholly within the space formed by the fillet surfaces 32 and the grooves 33.

Referring to Figs. 2 and 3, the ends of the inner tube stock T are first laid in the channel shape recesses 20 of the lower jaws 11 and fluid under pressure is then admitted to the cylinders 15 and 16 to move the platens 30 and the upper jaws 10 attached thereto towards the lower jaws 11 to clamp the inner tube stock as shown in Fig. 4. Alignment of the jaws is insured by engagement of the guide posts 27 in the slots 26. As best shown in the enlarged partial sectional view of Fig. 5, the folded

lateral edges L of the tube stock T occupy the spaces formed between the grooves 33 and the fillet surfaces 32 so that while pressure is exerted on the lateral edges L, the pressure is not so severe as to crush or crease the edges L and therefore cause cracking. By this construction, the pressure exerted by clamps 10 and 11 on the tube stock T is substantially uniform across the full width of the tube stock T and when the pressure is increased to bulge or extrude out the ends of the stock as shown in Fig. 7 in accordance with the method described in U. S. Patent No. 2,550,566, the bulging or extrusion of the trimmed ends will be substantially uniform across the full width of the stock T as shown in Fig. 6. Being firmly gripped across the full width, there is no chance of the stock slipping back between the jaws when the bulged ends are forced together to form a splice. Accordingly the splice is uniformly strong across the full width thereof and no weak spots are developed.

In Fig. 8, there is shown a slightly modified form of the invention. In this modification, grooves 33a are provided along the lateral edges of the recess 20a of the lower jaw 11a. The upper jaw 10a is provided with a flat surface 34a which terminates at opposite edges in concave surfaces 32a which form comparatively sharp edges 36a with the sides 35a of the jaw 10a. It will be noted that the resulting spaces formed between the grooves 33a and the surfaces 32a are similar to those formed between the grooves 33 and the fillet surfaces 32 of the embodiment shown in Fig. 1. The depth of the grooves 33a are similarly proportioned with respect to the tube stock T to be clamped as the grooves 31 and they function in the same manner to prevent crushing or creasing of the lateral edges L of the tube stock T.

In Fig. 9, there is shown still another modification. This modification in effect is a combination of those shown in Fig. 1 and Fig. 8 in that grooves 33b are provided in the upper jaw 10b and grooves 33c are provided in the lower jaw 11b. The individual grooves 33b and 33c are, however, substantially shallower than the grooves 33 of Fig. 1 or the grooves 33a of Fig. 8, inasmuch as the combined depth of grooves 33b and 33c are substantially equal to the depth of grooves 31 of Fig. 1. When the jaws 10b and 11b are moved together the grooves 33b and 33c form spaces which accommodate the lateral edges L of the tube stock T and thereby prevent severe crushing or creasing thereof while allowing the tube to be firmly gripped.

From the above description, it can be seen that there is provided a novel clamp structure for use in inner tube trimming and splicing machines. The clamp structure is characterized by the novel contour of the clamping jaws which permits the inner tube stock to be firmly and uniformly gripped across the full width of the tube stock without crushing or creasing the folded lateral edges of the stock, thereby reducing cracking or "fold breakdown." This novel contour of the clamping jaws permits the application of uniform pressure across the full width of the stock so that the ends can be uniformly bulged or extruded from the opposed faces of the jaws in accordance with the method described in U. S. Patent No. 2,550,566 and so that the bulged ends may be forced into butting engagement to form a splice without danger of the portions thereof adjacent the lateral edges slipping back in between the jaws. This uniform clamping of the stock also insures better and more uniform cutting or trimming of the ends of the stock preparatory to forming the splice. The smooth contour of the jaws of the clamps insure that no shear marks will be formed on the tubes.

It is to be understood that the above description and the drawings are for the purpose of illustration only and not by the way of limitation and changes in modification may be made therein without departing from the spirit and scope of the invention.

Having thus described our invention, what we claim and desire to protect by Letters Patent is:

1. A clamp for clamping tubular stock in flattened condition, comprising a pair of opposed clamping jaws providing flat opposed parallel clamping surfaces of substantially the same width between which the flattened tube stock is adapted to be clamped, the clamping surface of at least one of said jaws having inwardly curved, parallel concave grooves formed therein along opposite lateral edges thereof to accommodate the folded lateral edges of the tube, and means for moving said jaws toward and away from each other to clamp said flattened tube between said clamping surfaces.

2. A clamp for clamping tubular stock in flattened condition, comprising, a pair of opposed clamping jaws providing flat opposed parallel clamping surfaces of substantially the same width between which the flattened tube stock is adapted to be clamped, parallel sidewalls extending perpendicularly from the clamping surface of one of said jaws at opposite lateral edges thereof between which the other of said clamping jaws is adapted to be slidably received, the clamping surfaces of at least one of said jaws having inwardly curved, concave, grooves formed therein along each of its opposite lateral edges parallel to said sidewalls.

3. A clamp for clamping tubular stock in flattened condition comprising, a pair of opposed clamping jaws, one of said jaws having a channeled-shaped recess therein, said channeled-shaped recess having a flat base providing a flat clamping surface and perpendicularly extending flat parallel sidewalls, said other jaw being of a width substantially equal to the width of said channeled-shaped recess and adapted to be slidably received in said recess between said sidewalls, said other jaw being provided with a flat clamping surface parallel to the clamping surface of said one jaw, the clamping surface of at least one of said jaws being provided with an inwardly curved, concave, groove along each of its lateral edges parallel to said sidewalls to accommodate the folded lateral edges of said flattened tube stock.

4. A clamp for clamping tubular stock in flattened

condition comprising, a pair of opposed clamping jaws providing opposed parallel clamping surfaces of substantially the same width, each of said clamping surfaces comprising two laterally spaced, inwardly curved, concaved grooves connected together by a flat surface, said grooves serving to accommodate the lateral folded edges of said tube, and means for moving said jaws together to clamp said flattened tube stock between said clamping surfaces.

5. A clamp for clamping tubular stock in flattened condition comprising, a pair of opposed clamping jaws, one of said jaws having a channeled-shaped recess therein, said channel-shaped recess having a flat base providing a clamping surface and perpendicularly extending flat parallel sidewalls, said flat base and sidewalls being connected together by smooth, concave, fillet surfaces, said other jaw being of a width substantially equal to the width of said recess and adapted to be slidably received between said sidewalls, said other jaw being provided with a clamping surface comprising two inwardly curved, concave grooves extending along two opposite marginal edges of the jaw parallel to said sidewalls interconnected by a flat surface, the depth of said grooves being less than the thickness of the folded lateral edge of the tube stock.
